DISPLAY BOX

Samuel Braun, Rye, N.Y., assignor to B.C.N. Design Products, Inc., Amityville, N.Y., a corporation of New York

Filed Dec. 1, 1965, Ser. No. 15

Term of patent 14 years

(Cl. D63--12)

FIG. 1

FIG. 2

FIG. 3

FIG. 4

FIG. 5

FIG. 6

FIG. 7

FIG. 1 is a top plan view of a display box embodying my new design, the box being shown in closed condition;

FIG. 2 is a front elevational view thereof;

FIG. 3 is a rear elevational view thereof;

FIG. 4 is a side elevational view thereof;

FIG. 5 is a bottom plan view thereof;

FIG. 6 is a three-quarter perspective view, showing the display box in open condition; and

FIG. 7 is a fragmentary cross sectional view, on an enlarged scale, taken along the line 7-7 of FIG. 1.

The dominant portion of my design is that shown in solid lines.

I claim:

The ornamental design for a display box, as shown and described.
